2,466,417

APPARATUS FOR COVERING CORES

Lorne R. Guild, Baltimore, Md., assignor to Western Electric Company, Incorporated, New York, N. Y., a corporation of New York

Application December 22, 1947, Serial No. 793,175

3 Claims. (Cl. 87—29)

1

This invention relates to apparatus for covering articles, and more particularly to apparatus for applying braided coverings to groups of insulated conductors.

In the manufacture of strand assemblies, for example, multi-conductor cords, it is desirable in some instances to form a protective textile covering over a plurality of individually insulated conductors by braiding, knitting, or the like. If the textile covering is applied too tightly to the individually insulated conductors, the covering cuts into the insulated covering and impairs their insulating properties. On the other hand, if the textile covering is applied too loosely over the insulated conductor, slipping of the textile coverings occurs. In the past, integral members including conductor-guiding and braid-enlarging or softening pins have been used to control the tightness of the textile covering applied on the insulated conductors and to guide the conductors. However, if these softening pins are small they break easily, thereby requiring replacement of the entire device.

An object of the invention is to provide new and improved apparatus for covering articles.

A further object of the invention is to provide new and improved conductor-guiding and braid-softening devices for braiding machines.

An apparatus illustrating certain features of the invention includes means for guiding a plurality of conductors, a softening pin, and means for locking the softening pin detachably to the conductor-guiding means.

A complete understanding of the invention may be obtained from the following detailed description of an apparatus illustrating certain features of the invention, when read in conjunction with the appended drawings, in which:

Fig. 1 is a schematic, front elevation of an apparatus illustrating certain features of the invention;

Fig. 2 is an enlarged, fragmentary, vertical section taken along line 2—2 of Fig. 1;

Fig. 3 is an enlarged, horizontal section taken along line 3—3 of Fig. 2;

Fig. 4 is an enlarged, horizontal section taken along line 4—4 of Fig. 2;

Fig. 5 is an enlarged, horizontal view similar to Fig. 4;

Fig. 6 is an enlarged, vertical section taken along lines 6—6 of Fig. 5, and

Fig. 7 is an enlarged, vertical section taken along line 7—7 of Fig. 6.

Referring now in detail to the drawings, cordage 10 (Fig. 4) comprising a plurality of indi-

2

vidual insulated conductors 12—12 grouped around a textile cord 14 and a braided covering 16 is formed by a braiding machine 18, which braids strands 20—20 into the covering 16 and throws loop portions 22—22 of the conductors 12—12 out of the covering 16 at regularly spaced intervals. The braiding machine 18 is generally similar to that disclosed in W. T. Barrans et al. Patent 1,954,979, issued April 17, 1934.

The braiding machine 18 (Fig. 1) includes carriers 24—24 and a cylinder 30 at the top of which a guiding and softening device 32 is mounted. The conductors 12—12 pass upwardly, as viewed in Fig. 2, through needles 34—34 to the guiding and softening device 32. A support 35 mounted slidably in the cylinder 30 moves the needles 34—34 upwardly with respect to the cylinder 30 at regular intervals to form with a chuck 36 the looped portions 22—22. A tube 38 fastened rigidly to the cylinder 30 guides the stay-cord 14 up the cylinder 30 to the guiding and softening device 32. The position of the tube 38 at the periphery of the cylinder permits threading the stay cord through the tube without removing the chuck 36.

The device 32 (Fig. 6) includes a substantially frustoconical guide 40 and a pair of softening pins 42—42 each having a swaged end, of which a swaged end 44 of one of the pins is shown. The pins 42—42 are mounted slidably in spaced bores 46—46 (Fig. 5) formed in the guide 40, and are locked therein by a shoulder 48 formed on a double-size stud 50 (Fig. 6). The stud includes a small shank 52 threaded into a tapped bore 54 formed axially in the guide 40 and a large shank 56, which is designed to be threaded into a tapped bore 57 formed in a spider 58 fastened to the cylinder 30. The stud 50 may be disengaged from the guide 40 to permit removal and reinsertion or replacement of the softening pins 42—42.

The guide 40 is provided with a pair of large grooves 60—60 for guiding pairs of the conductors 12—12, and also is provided with a small groove 62 for guiding one of the conductors 12—12. The grooves 60—60 and the groove 62 are spaced 120° from each other and space the conductors around the axis of the guide. An L-shaped passage 64 guides the stay-cord 14 from the tube 38 (Fig. 2) to a position centered among the conductors 12—12.

Operation

The braiding machine 18 serves to bunch the conductors 12—12 around the stay-cord 14 and to braid the strands 20—20 into the covering 16

around the conductors 12-12 to form the cord 10, which is advanced upwardly, as viewed in Fig. 2. The braid is formed around the conductor 12-12 at a point in the braiding machine 18 about half way up the softening pins 42-42 so that the softening pins 42-42 act as a braiding center. The softening pins 42-42 are spaced apart a distance such that they cause the covering 16 to be larger than if they were not present so that the degree of tightness of the covering 16 is optimum. The stay-cord 14 is brought into the center of the conductors 12-12 by the guide 40, which also spaces the conductors 12-12 around the stay-cord 14 as the conductors are bunched together by the action of the strands 20-20 being braided into the covering 16.

The device 32 may be disassembled in order that the pins 42-42 may be repaired or replaced. This device accurately spaces the conductors 12-12 and the stay-cord 14 as these elements are moved together by the covering 16. The softening pins 42-42 also serve to hold the cordage 10 centered with respect to the braiding machine as the covering 16 is formed around the conductors 12-12.

What is claimed is:

1. In an apparatus for forming coverings over cores including means for advancing a plurality of core elements along a predetermined path and means for forming a textile covering around the core elements at a predetermined point in said path, a device for guiding the core elements and for enlarging the covering, which comprises a core guide provided with a plurality of openings spaced therearound for spacing the core elements with respect to each other as they are advanced toward said point in the path thereof, said guide being provided with a passage therein for guiding at least one of said elements into the center of the remainder of the core elements, a pin, and means for securing the pin to the guide in a position in which the pin projects through the covering forming point.

2. In an apparatus for forming coverings over cores including means for advancing a plurality of core elements along a predetermined path and means for forming a textile covering around the core elements at a predetermined point in said path, a device for guiding the core elements and for enlarging the covering which comprises a

core guide provided with a plurality of grooves spaced therearound for guiding the core elements in a predetermined relation with respect to each other as they are advanced toward said point in the path thereof, said guide being provided with a bore extending therethrough, a pin having a head on one end thereof designed to fit into the bore and extend beyond the guide, and means for pressing the head of the pin against the guide to lock the pin to the guide.

3. In an apparatus for braiding a covering around a plurality of individually insulated conductors and a stay-cord including means for advancing a plurality of individually insulated conductors and a stay-cord centrally located among the conductors along a predetermined path and means for braiding a plurality of textile strands into a covering at a predetermined point in said path, a guiding and softening device, which comprises a frustoconical guide provided with a plurality of grooves spaced equi-angularly therearound, at least one of the grooves being designed to receive two of the insulated conductors therein and one of the grooves being designed to receive only one of the insulated conductors therein, said guide also being provided with a substantially L-shaped passage leading from one side thereof to the longitudinal axis thereof for guiding the stay-cord to a position between the conductors advanced through the grooves in the guide, said guide also being provided with a pair of bores formed therethrough parallel to the longitudinal axis thereof, said guide also being provided with a tapped bore located axially therein, a pair of softening pins having enlarged heads positioned in the pair of bores and projecting through said covering forming point, and a threaded member designed to be screwed into the tapered bore in the guide for locking the softening pins in the bores in the guide.
